GUIDED MISSILE

Earl C. Sparks, Jr., Cranston, R. I., and Moulton
B. Taylor, Huntingdon Valley, Pa.

Application July 2, 1946, Serial No. 680,905

21 Claims. (Cl. 244—77)

(Granted under the act of March 3, 1883, as
amended April 30, 1928; 370 O. G. 757)

1

This invention relates to guided missiles, and more particularly, this invention relates to guided missiles capable of computing and traveling along an intercept course to a preselected target.

A primary object of this invention is to provide a missile with automatic devices to compute and control said missile along an intercept course to a preselected target.

Another object is to provide a guided missile with means of selecting a particular object as the target.

A further object is to provide a guided missile that requires no remote control for its operation after the target selection has been made.

Other objects and advantages of this invention will be apparent from the following description.

Reference is now made to the accompanying drawings wherein corresponding numbers refer to corresponding parts and in which:

Fig. 1 is a view of the missile, towing craft, and target after the missile has been released from the tow cable;

Fig. 2 is a block diagram of the control units, radar, and antenna mechanism of the preferred embodiment;

Fig. 3 is a schematic diagram of the control units and circuits including an isometric view of the antenna mechanism;

Fig. 4 is a sectional view of a three-wire conductor tow cable;

Fig. 5 is an isometric presentation of the intercept computation problem in the vertical plane;

Fig. 6 is an isometric presentation of the intercept computation problem in the horizontal plane;

Fig. 7 is an isometric presentation of the intercept computation problem in both horizontal and vertical planes;

Fig. 8 is a sectional view showing the features of a gyroscope utilized by this invention; and

Fig. 9 is a block diagram of an alternate arrangement of the proposed invention.

The invention consists of a radar set and appropriate control equipment cooperating to guide an airborne missile along an intercept course to the point of impact with a selected target. The radar set selected for use in this invention must provide signals indicative of the relative position of the selected target with respect to the axis of the antenna in addition to the customary requirements familiar to those skilled in the art. The control equipment includes cageable gyro-

scopes, servomotors, pulleys and control cables, a suitable mechanical system cooperating with slewing motors to control an antenna in both azimuth and elevation, an audio frequency-operated relay selector, an automatic control device as described in the application Serial No. 592,627, series of 1935 issued to Moulton B. Taylor, co-inventor herein, now Patent No. 2,432,548 issued December 16, 1947, a three-conductor tow cable, and an electrical intelligence combining device hereinafter to be referred to as a mixer.

Prior to the application of this invention for the purpose of guiding the missile along an intercept course to a target, the missile is towed by the three-conductor tow cable and a parent aircraft. During the towing period, the radar equipment is tuned from the parent aircraft by a technician operating switches that select one or a combination of several audio frequency voltages that are transmitted to the relay selector in the missile along one conductor of the three-conductor tow cable, thereby completing the necessary circuits through the audio-frequency selected relay contacts or combinations of these 25 relay contacts to tune the radar equipment. For the purpose of maintaining the missile in stable flight and at a fixed position relative to the parent aircraft during the towing period, an automatic control device is employed. Of the group of switches accessible to the technician 30 aboard the parent craft, one switch is reserved to send a final audio frequency voltage along the conductor of the tow cable to operate a single relay that, first, completes the circuits to allow the invention to compute the intercept course 35 to the target and thus guide the missile accordingly; second, disengages the automatic control device; and finally, disconnects the tow cable from the missile.

Fig. 1 shows the missile immediately after the tow cable has been disconnected from the missile, thus allowing the parent craft to return to a safe operating area.

Included in the procedure of computing the intercept course is the application of direct-current voltages to slewing motors which are suitably geared to the antenna mounting and thus control the positioning of the antenna beam. These direct-current voltages are outputs from a sensing circuit provided in the radar equipment and are of the polarity and amplitude indicative of the direction and amount that the target deviates angularly from a reference axis of the antenna beam. The elements herein considered cooperate 55 so as to cause the axis of the antenna beam to

Continually reposition itself to bear on the selected target. Flexible cabling operating over suitable pulleys serve to link the described antenna movements to produce a displacement of the gyroscopic orifices of the yaw and pitch controlling gyroscopes as necessary. Direct-current output voltages appearing as a function of the relative orifice displacement in the gyroscopes control aileron and elevator servomotors which in turn impart a movement to the rudder, elevators and ailerons of the missile, thereby positioning the missile on an intercept course. A follow-up system returns the gyroscopic orifices to a neutral position about which they remain until again demanded to recorrect the missile position due to changes in relative azimuth and elevation of the target.

In the embodiment shown in the accompanying drawings, and in particular Fig. 2 wherein the solid connecting lines indicate electrical connections and the broken connecting lines indicate mechanical linkages, the invention consists generally of a radar system indicated generally at 13 and the necessary control units and circuits, and in addition, an antenna 17 with suitable mountings to allow control in both azimuth and elevation. Separate servomotors 50 and 83 provide the necessary control of the antenna in the two directions. Gyroscopes 56, 87, and 105 and accompanying roll trim motors 102, elevator servomotors 60, and aileron servomotors 110 affect the control airfoils 75, 118, and 123 of the missile to keep the missile on the intercept course, utilizing the radar-controlled antenna movements to provide a properly proportioned displacement of the orifices in the gyroscopes. A suitable follow-up system is employed to neutralize the gyroscopes and reestablish equilibrium in the system. The gyroscopes 87 and 56 controlling yaw and pitch respectively are reverse-connected so that an error signal introduced in either of the gyroscopes by virtue of an angular displacement of the missile will provide signals to the respective servomotors producing a movement of the control airfoils so as to cause the missile to respond in such manner as to introduce further error in the gyroscopes. "Reverse connected" as used here, indicates that the external wires 69 and 70 from space reference gyro 56 and the external wires 98 and 99 from the space reference gyro 87 are reversed in polarity to gyro output terminals so that they produce a motion of the airfoil in response to an angular displacement of the aircraft and uncaged gyro that is opposite the motion of an airfoil in response to the same angular displacement of the aircraft in normal automatic pilot operation; i. e., in normal automatic pilot operation the electrical or mechanical connection between an uncaged gyro and an airfoil is such that an angular displacement of the aircraft to the right (or up in pitch axis) causes a gyro error which in turn, due to the polarity of wires from gyro to servos, produces an airfoil motion that causes the original angular displacement of the aircraft to be decreased and removed by angular motion of the aircraft to the left (or down). In the operation of an uncaged gyro and the airfoil as used in this application, the electrical connection between the uncaged gyro and the airfoil is such that an angular displacement of the aircraft to the right (or up in pitch axis) causes a gyro error which, in turn, due to the polarity of wires from gyro to servo, produces an airfoil motion that causes the original angular displace-

ment of the aircraft to be increased by additional angular motion to the right (up in pitch axis).

The purpose of introducing "further error in the gyroscopes" is the basic way of obtaining the lead angle necessary to produce a navigational or intercept course instead of a homing course. In producing further error due to an angular deviation of the aircraft, the gyros have now caused the aircraft to move ahead of the target. This further error introduced by the gyroscopes being reversed connected now has to be removed by the target seeker moving back on the target till a proper equilibrium has been reached between the gyro's tendency to produce this further error and the target seeker's ability to follow the target and remove the gyro error signal. In the normal sequence of events in the operation after release of the towed aircraft the gyro would remain caged until there was no chance of losing return radar signal and at this time the AVC voltage would uncage the gyro. This would leave the antenna in full control to remove the uncaged gyro ability to add on an ever increasing turn. The antenna angular motion with caged gyro produces straight homing course. With an uncaged gyro reversed connected to add error angle, the antenna, gyro and aircraft produces an intercept course with proper lead angle when in equilibrium and continues to correct to the course. The characteristics thus established in the gyroscopes provide a basis for the device's ability to guide the missile along the automatically computed intercept course to the target. A third gyroscope 105 connected in the conventional manner is provided for roll stabilization. The servomotors controlled by the gyroscopes may be electrically powered, or they may be vacuum or hydraulically operated with proper electric valves to control clockwise or counterclockwise rotation as desired.

The operations of the control system while the missile is being towed into its effective operating range, which is limited only by inherent range limiting characteristics of the radar equipment employed, is dependent upon an automatic control system which is put in operation prior to take-off and disconnected by the audio-frequency tow line voltage energizing the appropriate relay contained in the selector.

In the embodiment illustrated by Fig. 3, the axis 7 of the parabolic reflector 8 is seen to be mounted at a small angle with respect to the fore-and-aft reference axis 9. The parabolic reflector 8 revolves about the axis 9 driven by the drive motor 10 through gear 11 meshing with gear 12 which is rigidly fixed to the parabolic reflector 8. This revolution will cause the axis 7 of the parabola to generate a cone of revolution. Characteristics of the parabolic reflector 8 cause the radio-frequency energy developed by the radar equipment 13 to radiate and the reflected radio-frequency energy to be detected only along a very narrow beam. The combined effect of the narrow beam and the revolution is to produce a field pattern that is conical in shape. Voltage indicating the position of the antenna beam in its cone of revolution, i. e., up, down, right, or left, and other necessary control voltages complete their link between the antenna system and the radar equipment 13 via the multi-conductor cable 16. The radio-frequency energy is conveyed to and from the radar equipment 13 by means of the coaxial cable 14 and the rigid coaxial conductor 15. The radar equipment 13 receives the proper operating voltages from a separate power supply 20. All operating voltages,

both input and output, but not including the voltages from the power supply 20, essential to the operation of the radar system 13 are first impressed on various terminals in a junction box 21 where they are properly distributed to the various units of the embodiment. Direct-current voltages indicative of the position of a selected target with respect to the fore-and-aft reference axis 9 are fed to the junction box 21 through the multi-conductor cable 22 where these voltages are distributed. One series of these voltages appears on the single-conductor cables 23, 24, 25 and 26. The amplitudes of these voltages are proportional to the degree of displacement of the target from the fore-and-aft reference axis 9. A second series of the aforementioned voltages is impressed on the multi-conductor cable 27 to a mixer 28 where they are properly combined and transmitted to the parent aircraft along one conductor 29 of the towline 32. Referring to Fig. 4, which is a sectional view of the towline 32, the outer casing 33 receives the load produced by towing and also houses the three single conductor cables 34, 35 and 36 and their respective conductors 29, 30 and 31. As described above, direct-current voltages properly combined are impressed on conductor 29 for transmission to the parent aircraft. Similarly, conductor 30 is used for transmission of the video, trigger, and gate output of the radar system 13 entering the mixer 28 through multi-conductor cables 22 and 27 and the junction box 21. Conductor 31 is used for transmission of ten different audio frequencies generated by an audio frequency oscillator in the parent plane to a selector 40. A panel of ten switches in the parent aircraft provide selection of a desired audio frequency to be generated by the audio frequency oscillator. The various audio frequencies introduced into the selector 40 are fed into frequency selective circuits suitably coupled to a series of ten relays, each circuit being tuned to one of the ten audio frequencies and so coupled as to operate a single relay in response to an audio input of the appropriate frequency. The contacts of the various relay circuits are connected to the radar system through the multi-conductor cables 41 and 22 and the junction box 21 to perform various operating and tuning adjustments. One audio frequency and its associated relay circuit is reserved for disengaging the automatic control system 42, arming the missile, and finally disconnecting the tow cable itself.

An output voltage proportional to the amplitude of a received radar echo signal commonly referred to as automatic volume control voltage or simply AVC voltage is impressed on the electrical uncaging devices 61 and 92 through multi-conductor cable 22, junction box 21 and the conductors 43 and 44 and is thus utilized to automatically uncage the space reference gyroscopes 56 and 87.

The trunnion 48 and a similar trunnion (not shown) on the opposite side of the antenna assembly allows rotation in the vertical plane of the parabolic reflector 8 about an axis 49. This rotation is controlled by the voltages appearing on conductors 23 and 24 which are proportional to the deviation of the target in the vertical plane from the fore-and-aft reference axis 9. The relative amplitudes of these voltages determine the direction of rotation of the servomotor 50. The shaft of the motor 50 is rigidly fixed to a pinion gear 51 which meshes with the gear segment 52 rigidly fixed to the antenna assembly. Thus rotation of the motor 50 produces rotation of the

parabolic reflector 8 about the axis 49, and connections are made to the motor 50 in such a manner as to cause rotation of the parabolic reflector 8 in a direction to align the target with the fore-and-aft reference axis 9. It is to be understood at this time that the mechanical features of the antenna mounting as described do not restrict this invention to that specific type of mounting. Affixed to the gear segment 52 and 10 adjustable in position radially is a free-rotating pulley 53 over which is run suitable cabling 54-54'. One side of the cable 54' connects with the drum 55 of the gyroscope 56 after passing over a suitable pulley system 57, while the other side of the cable 54 passes over a suitable pulley system 58 to the arm 59 of an elevator servo 60. The gyroscope 56 has a suitable suction connection 64 and battery connection 65, the battery circuit being from the battery connection 65 through the conductor 66 and the main on-off switch 67 to the battery 68 with its proper ground connection. The gyroscope actuated pick-off contacts of gyroscope 56 are connected by the conductors 69 and 70 to terminals 71 and 72 respectively of 20 the servo 60. The arm 59 and cable 54 provide the follow-up system for the gyroscope 56. A second cable 73 passing over a suitable pulley 74 controls the action of the elevator 75.

Directional control of the antenna in azimuth 30 is provided by the action of the antenna assembly mounting table 79 which rotates in the horizontal plane about an axis 80. The table 79 is provided with gearing 81 along a segment of its periphery that is meshed with the pinion gear 82. The rotation about axis 80 is controlled by the voltages 35 appearing on conductors 25 and 26, which are proportional to the deviation of the target in the horizontal plane from the fore-and-aft reference axis 9. The relative amplitudes of these 40 voltages determine the direction of rotation of the servomotor 83 to which they are connected. The shaft of the servomotor 83 is rigidly fixed to the pinion gear 82, and hence, controlling of the rotation of the servomotor 83 will control the 45 rotation of the parabolic reflector 8 about the vertical axis 80. Affixed to the table 79 and adjustable in position radially is a free-rotating pulley 84 over which is run suitable cabling 85-85'. One side of the cable 85' connects with the drum 86 of the gyroscope 87, whereas the 50 other side of the cable 85 passes over suitable pulleys 88 and 89 to the 90° yoke 90 of a proportional roll trim motor 91. The gyroscope 87 has a suitable suction connection 95 and battery connection 96, the battery circuit being from the 55 battery connection 96 through the conductor 97 and the main on-off switch 67 to the battery 68. The gyroscopic-actuated pick-off contacts of gyroscope 87 are connected by the conductors 98 and 99 to terminals 100 and 101 respectively of the roll trim motor 91. One arm of the yoke 90 and cable 85 provides the follow-up system for the gyroscope 87. Contained on the other arm of the yoke 90 is a pulley 102 over which is passed the cabling 103-103', one side 103' being connected to the drum 104 of a vertically stable gyroscope 105, and the other side 103 being connected to the arm 109 of the servo 110 after passing over a suitable pulley 111. A suction connection 112 is provided for the gyroscope 105 as is a battery connector 107 to the battery connection 108. The gyroscopic-actuated pick-off contacts of the gyroscope 105 are connected by the conductors 113 and 114 to terminals 115 and 116 of the aileron servomotor 110. There are three cable connec-

65

70

75

tions made to the arm 109, the previously described cable 103 providing follow-up for the gyroscope 105. A cable 117 connected to arm 109 provides control of the right aileron 118 after passing over suitable pulleys 119 and 120. For clarity, only one aileron has been shown, although an oppositely acting left aileron is of course provided. A cable 121 also connected to the arm 109 leads over a suitable pulley system 122 to control the rudder 123.

In placing the device into use, a conventional system inspection is made prior to take-off at which time the main on-off switch 67 is turned on, and the automatic control or feeler system 42 put into operation to control the missile until its point of release. When the missile is airborne and being towed by the parent craft by the three-conductor tow cable 32, the radar operator aboard the parent craft performs the tuning and adjustment of the missile-borne radar equipment 13. Conductors 29 and 30 contained in the tow cable 32 provide the radar operator with sufficient information, i. e., video response, gates, trigger pulses, test voltages, etc., to enable him to perform these adjustments. This information is first combined in the mixer 28 in suitable form for simultaneous transmission along the conductors 29 and 30 and then decomposed in the parent craft to present the information in its original form. Remote tuning and adjustment is made possible by the ten selector switches, the associated audio frequency generators in the parent craft, the three-conductor tow cable 32, and the selector 40 and mixer 28 in the missile; the operation having been previously described in this specification. Upon selection of an appropriate target, the pilot of the parent craft is instructed to fly a "dead-reckoning" intercept course to the target; and the radar operator positions that target by controlling the selector circuits of the radar equipment 13 in the missile. The antenna system of the radar equipment 13 now is able to provide sensing voltages on the conductors 23, 24, 25 and 26 that are indicative of the selected target's position with respect to the fore-and-aft reference axis 9-9'. A final audio voltage is sent to selector 40 by operation of the proper switch in the parent craft, and a circuit which is thereby completed disengages the automatic control system 42, arms the missile, and disconnects the tow cable 32. At the time of release, the antenna bears on the target and the missile on a course as judged previously by the pilot of the parent craft; and the components of the invention are in a state of equilibrium. This equilibrium will not be disturbed until an angular displacement of the target with respect to the fore-and-aft reference axis 9-9' occurs of sufficient magnitude to be detected by the antenna and radar sensing circuits. The radar equipment 13 detecting the selected target now provides a sufficient AVC voltage through conductors 43 and 44 to the uncaging elements 61 and 92 allowing the "space reference" gyroscopes 56 and 87 to uncage. The elevation control of the missile will be considered at this time, the azimuth control to be considered later.

Referring to Fig. 5, at the point of release of the missile from the parent craft 130, the antenna and radar sensing circuits are not able to detect the angular displacement of the target as it moves vertically from its starting point 140 until the missile has reached a point 131 along its path 130-140, whereupon the target has moved to a point 141 forming the angle α . As a

result of this angular displacement α , voltages will appear on conductors 23 and 24 causing the antenna axis to align itself with the target, the voltages on conductors 23 and 24 being the up and down indicating voltages controlling the direction of rotation of the servomotor 50. The antenna has now rotated upward through an angle α in effect shifting the fore-and-aft reference axis 9 from coincidence with the line of flight 130-140 to a new position 131-141. This upward rotation will cause the free-running pulley 53 to move downward, causing slack in the cable 54-54'. The spring loaded drum 55 of gyroscope 56 will absorb this slack by its rotation, thereby disturbing the neutral position of the gyroscope suction orifice with respect to the gyroscopic positioned deflecting vane. Resulting from this movement, there appears on conductor 69 a voltage that is applied to terminal 71 of the elevator servomotor 60 producing a clockwise rotation of the servo motor arm 59, i. e., to the left. The movement of arm 59 acts on the cable 73 operating over pulley 74 in such a manner as to raise the elevator 75 and cause the missile to travel upward. Occurring simultaneously with the change of the missile's flight attitude is the action of the follow-up cable 54' acting so as to remove the suction orifice displacement caused by the antenna movement. Because of the reversed connections to the gyroscope pick-off contacts, the plane's upward movement displaces the gyroscope orifice with respect to the gyroscopic fixed position of the deflecting vane so as to maintain voltage on conductor 69 providing continuous clockwise torque on arm 59 of the servo 60. The antenna being affixed to the missile will be displaced from the target as the missile moves upward. The antenna and radar sensing circuits detecting this displacement act so as to reverse the voltage in conductors 23 and 24, and the antenna moves downward as to reposition itself on the target. This downward motion of the antenna displaces the gyroscope orifice in a direction as to attempt to provide a downward voltage on conductor 70 and does provide this voltage when the orifice movement in this direction becomes greater relative to the displacement being provided in the opposite sense by the missile's changing motion upward. When the down voltage appears on conductor 70 applied to terminal 72 of the elevator servo 60, the arm 59 moves to the right to its neutral position, thereby neutralizing the elevator 75 and also neutralizing the gyroscope 56 on its newly established stabilization axis 131-133 of Fig. 5. Resulting from the simultaneous movements of the antenna axis 9-9' and the missile's flight path, the missile now travels along a course 131-133 while the antenna reference axis 9 coincides with the line-of-sight from missile to target 131-141. The antenna axis has shifted through an angle α , whereas the missile path has shifted through an angle depending upon the ratios set up in the control system. The choice of this ratio is dependent upon the definite damping requirements associated with the particular type missile or airframe in use, and determination of the concise ratio for a specific type airframe will have to be made from an actual test flight of the type airframe in question. For example, in test flights using this invention in a twin-engine aircraft of Beechcraft manufacture, it has been found that a ratio of 2.7:1 provides the most efficient operation. Ratios are varied in the elevation control system by varying the radial position of the pulley 53 on the gear seg-

ment 52 and/or also by varying the length of the arm 59 of the elevator servo 60. Thus as the antenna axis shifts through an angle α , the missile changes course by an angle R times α where R is the ratio selected wherein selection of the proper ratio for a specific type airframe will provide for that airframe the proper corrections to guide it along an intercept course to a point of impact with the selected target. Thus at any point along the flight path 131-133, the antenna 10 will bear on the target. For instance, at a point 132, the target has moved to point 142, and the antenna axis 132-142 being parallel with the previously corrected orientation 131-141 intersects the target path at point 142, the target 15 location for missile position 132. At point 133-143 target and missile paths intersect, hence, the point of contact and detonation of the previously-armed missile.

In considering the azimuth control of the missile, reference will be made to Figs. 3 and 6. From the point of release of the missile from the parent craft 130, the missile will have to travel to some point 131, whereupon the radar and antenna sensing circuits can detect angular movement of the target in the horizontal plane. The target traveling along its path 140-163 has advanced to a point 161 forming the angle β between the missile path 130-140 and the line of sight from the missile's present position 131 and the target's position 161. As a result of this angular displacement β of the target with respect to the fore-and-aft reference axis 9, voltages will appear on the conductors 25 and 26 with such amplitudes and polarities as to cause the servomotor 83 to rotate in a counterclockwise direction. As a result of this rotation, the fore-and-aft reference axis will shift to the right and reposition itself on the target now at point 161, i. e., the fore-and-aft reference axis now coincides with the line of sight 131-161. Rotation about the axis 80 has caused the free-rotating pulley 84 to move to the left causing slack to appear in the cabling 85-85'. This slack will be absorbed by the rotation of the spring-loaded drum 86 of the reverse-connected gyroscope 87, thereby displacing the gyroscope orifice in a direction so as to produce a voltage on conductor 98. The conductor 98 connects with the contact 100 which controls the counterclockwise rotation of the 90° 50 yoke 90 of the proportional roll trim motor 91. The rotation of the 90° yoke 90 allows the follow-up cable 85 to remove the gyroscope orifice displacement of gyroscope 87 previously placed there as a result of the antenna rotation. The rotation of the 90° yoke 90 also produces a slack in the cabling 103-103' which is absorbed by the rotation of the spring-loaded drum 104 of the conventionally-connected vertically stable gyroscope 105, the rotation producing a displacement of the gyroscope orifice and thus causing a voltage to appear on the conductor 114. The signal appearing on conductor 114 produces a counter-clockwise rotation of the arm 109 of the aileron servo 110. By means of the cables 117 and 121, the rotation of the servo arm 109 imparts a mechanical action to the aileron 118 and rudder 123 respectively, causing the missile to bank to the right. As a further result of the rotation of the arm 109, the follow-up cable 103 acts to 60 partially remove the previously placed orifice displacement in the gyroscope 105. As the missile banks to the right, several actions occur in the control elements simultaneously. As a result of the reversed connections to the gyroscope 87 and 70

the missile's change of course to the right, the relative orifice and vane displacement thus produced tend to maintain the right controlling voltage to contact 100 on conductor 98 whereas the relative displacement of the elements of the conventionally-connected gyroscope 105 tend to produce a left controlling voltage on conductor 113 in opposition to the tendency in the opposite sense produced by the action of cable 103'. The antenna is being shifted to the left at this time in order to continue bearing on the target. Thus the cable 85 produces a rotation of the drum 86 displacing the orifice of the gyroscope 87 sufficiently to counteract the displacement in the opposite sense caused by the missile's change of course. Simultaneously, the missile's changing attitude has provided sufficient displacement to override the displacement in the opposite sense by the shift in position of the 90° yoke 90 and a left control voltage appears on conductor 113 whereupon the aileron servomotor 110 rotates in a clockwise direction to return its arm 109 and the control surfaces 118 and 123 linked thereto into a neutral position. The follow-up cable 103' acts on the drum 104 to reestablish equilibrium in the gyroscope 105. Thus both gyroscopes 87 and 105 have been neutralized about a new stabilization axis and equilibrium again established while the missile returns to its new flight attitude and flies along its new course 131-153 since the movement of the arm 109 allowed the rudder and aileron surfaces to return to their neutral positions. The antenna fore-and-aft reference axis 9-9' now coincides with the line of sight 131-161 from the missile to the target now at point 161. Thus the antenna axis has been shifted through an angle β , whereas the missile path has shifted through an angle dependent upon the ratios existing in the azimuth control system. It will be apparent that the damping characteristics of the particular type missile or airframe in use must be considered in the selection of the ratios to be used in the azimuth control unit as in the elevation control unit as previously described. Ratios are varied in the azimuth control unit by changing the radial position of the pulley 84 on the table 79 and/or also by varying the lengths of the arms of the 90° yoke 90 of the roll trim motor 91 and the arm 109 of the aileron servo 110. Determination of the proper ratio to be used for a specific type airframe will be made from an actual test flight of the type airframe in question, the limits of the ratio to be used in general falling within the limits as determined for the elevation system previously. Again selection of the proper ratio for a specific type airframe will provide for that airframe the proper corrections to guide it along an intercept course to the point of impact with the target. Thus, in the example depicted by Fig. 6, it can be seen that at any point along the flight path 131-153, the antenna will bear on the target. For instance, at a point 152, the target has moved to a point 162, and the antenna axis 152-162 being parallel with the previously corrected orientation 131-161 intersects the target path 140-163 at the point 162. At the point 153-163 the target and the missile paths intersect, hence the point of contact and detonation of the previously armed missile.

Treating the elevation and azimuth control circuits separately is analogous to the angular resolution of the simultaneous effect of both control systems into quadrature effects. Consequently, combining the two effects produces the

simultaneous control actually provided in this invention. Referring to Fig. 7, it can be seen that the numbered points therein corresponding to identical numbered points in Figs. 5 and 6 thus depict identical points. Hence, the path 140—163 represents vectorially the target path in the horizontal plane; 140—143, the target path in the vertical plane; 131—163, the corrected missile path in the horizontal plane; 131—143, the corrected missile path in the vertical plane; etc. Thus the path 140—193 is the vector summation of paths 140—143 and 140—163, and represents the path of the target in space; whereas the path 131—203 is the vector summation of paths 131—143 and 131—163 and represents the corrected path of the missile in space. Combination of the quadrature antenna beam directions 131—141 and 131—161 provide the antenna beam space direction 131—191; and at any point along the flight path 131—203, the antenna will bear on the target. For instance, at a point 202, the target has moved to a point 192, and the antenna axis 202—192 being parallel with the previously corrected orientation 131—191 intersects the target path 140—203 at the point 192. At the point 193—203, the space paths of the antenna and the missile intersect, hence, the point of contact and detonation of the previously armed missile.

The operation of the space reference gyroscope 56 will be described more specifically with reference to Fig. 8 which is a cut-away view of the gyroscope 56 and other cooperating elements and in which corresponding numbers refer to corresponding parts in the preferred embodiment of Fig. 3. The cable 54', which is connected to the free-rotating pulley 53 of the antenna gear segment 52, operates over the pulley 55 which is provided with spring loading due to the action of the spring 170. The spring loading thus produced delivers a torque to the pulley 171 which is rigidly affixed to the shaft 172 and thereby produces a clockwise rotation of the shaft 172 when the cable 54' is payed out as by an upward shift of the fore-and-aft reference axis 9. The orifice positioning gear 173 is attached to a shaft whose axis is coincident with the longitudinal axis 174—174' of the gyroscope 56. This gear 173 meshes with the pinion 175 which is rigidly fixed to the shaft 172. Thus an upward motion of the cable 54' will cause clockwise rotation of the shaft 172 and pinion 175, thereby controlling a counter-clockwise rotation of the gear 173. An air-tight slot 176 is provided in the end plate of the gyroscope 56 to allow movement of the connecting pipe 177 leading to the Sylphon 178. The gyroscopic controlling elements include the suspension gimbals 181 in the vertical plane and 182 in the horizontal plane, suitable pivots 183 and 183' being provided at the intersection of the gimbal 182 with the longitudinal axis 174—174'. Also mounted on the gimbal 182 at its point of intersection with the longitudinal axis 174—174' and perpendicular to that axis 174—174' is the gyroscopic-positioned vane 184 covering one-half of the orifice 185 with all elements in a neutral position. A rotor 186 is mounted on the gimbals 181 and 182, rotation being provided by suitable mechanical, electrical, or air devices. An uncaging device 61 operated by the AVC voltage appearing on conductor 44 allows movement of the gyroscope case with respect to the gyroscope elements 181, 182, 184, and 186 about an axis coincident with the longitudinal axis 174—174' when the missile changes flight attitude in the vertical transverse plane.

The Sylphon 178 expands and contracts in accordance with the amount of suction applied through the connecting pipe 177, the amount of suction being determined by the position of the vane 184 with respect to the orifice 185. Mechanical linkages are provided to selectively furnish voltage to the conductors 69 and 70, expansion of the Sylphon 178 causing contact 188 to move to the right completing the circuit from the battery contact 65 to the conductor 69, whereas contraction of the Sylphon 178 causes contact 188 to move to the left completing the circuit from the battery contact 61 to the conductor 70. A small bleed hole 189 open to the atmosphere is provided in the Sylphon 178 allowing a small air intake, thereby permitting the Sylphon 178 to expand when the suction is substantially cut off by total coverage of the orifice 185 by the vane 184. The size of the bleed hole 189 is such as to provide an equilibrium condition with the orifice 185 one-half covered by the vane 184, wherein the contact 188 remains in a neutral position at the center of its travel providing an open circuit from the battery contact 65 to either conductor 69 or 70. Thus a slight covering of the orifice 185 will cause expansion of the Sylphon 178 and completion of the circuit to conductor 69, whereas a slight uncovering of the orifice 185 will cause contraction of the Sylphon 178 thereby completing the circuit to the conductor 70. A vacuum source, preferably an external vacuum pitot tube in the air-stream surrounding the missile, is connected to the case of the gyroscope 56 through the tubing 64.

Thus, in conjunction with the broad description of the pitch control of the missile, a paralleled description follows, but more specifically describing the actions taking place in the gyroscope 56 itself. In the problem taken up in reference to Fig. 5, the initial disturbance resulted from an antenna movement upward of α degrees, causing slack to appear in the cable 54'. The slack is absorbed by clockwise rotation of the pulley 55. The clockwise rotation of the pulley 55 thus produces a counterclockwise rotation of the gear 173 thereby moving the orifice 185 downward to allow the vane 184 to more completely cover the orifice 185. The Sylphon therefore expands and a voltage appears on conductor 69 producing a clockwise rotation of the arm 59 of the elevator servo 60 thereby raising the elevator 75 to cause the missile to travel upward, the follow-up cable 54 acting so as to remove the displacement of the orifice 185 with respect to the vane 184. As the missile changes its attitude, the gyroscope case affixed to it also changes attitude thereby disturbing the relative position of the orifice 185 with respect to the gyroscopic fixed position of the vane 184. This action causes the voltage on conductor 69 to so remain. As the antenna moves down to counteract the effect of the upward moving missile, tension is induced in the cable 54' thereby displacing the nozzle opening 185 in a direction attempting to increase the suction. As increased suction is induced when the change of displacement in this sense becomes greater relative to the displacement of the vane 184 acting to decrease the suction as a result of the missile's upward change of direction. The increased suction in the pipe 170 causing contraction of the Sylphon 178, closes the battery circuit to conductor 70 thereby producing a counterclockwise rotation of arm 59, returning the arm 59 to its neutral position. The motion of the arm 59 acting on the cable 73 neutralized

the elevator 275 and as a result of its action on the follow-up cable 54, the nozzle opening 185 has been displaced into a neutral position about the newly established stabilization axis of the gyroscope 56.

The operation of the gyroscope 87 is identical with the described operation of gyroscope 56, although it will be apparent that the gyroscope 87 is provided for azimuth control, whereas the gyroscope 56 is provided for elevation control. The vertically stable gyroscope 105 is connected in the conventional manner, and it is felt that sufficient prior art is available so as not to warrant a detailed explanation of its operation.

Fig. 9 shows an alternate form of the proposed invention wherein the solid connecting lines indicate electrical connections, and the broken connecting lines indicate mechanical linkages, and wherein, for ease of identification, the number parts are 200 units larger in numerical value than the corresponding parts of the preferred block-diagram of Fig. 2. The foregoing description of the preferred embodiment enables elimination of detail in the block diagram of Fig. 9 for clarity and ease in understanding this alternate form. The arrangement of the parts of Fig. 9 is similar to the arrangement of Fig. 2. The deviation appears in the connections between the radar unit 213, the gyroscope pick-offs, and the several servomotors. The radar equipment 213, which is understood to include all detailed elements of the radar equipment of Fig. 3, provides azimuth control voltages to the proportional roll trim motor 302 which affects the stable vertical gyroscope 395 to operate the remainder of the elements in the azimuth system; i. e., the aileron and rudder servomotor 310, aileron 318, and rudder 323; and in addition, provides follow-up to the space reference gyroscope 287. The output from the pick-off means of gyroscope 287 controls the antenna azimuth servomotor 283 to position the antenna 217 in azimuth.

The radar system 213 also provides elevation control voltages to the elevator servo 260 to control the elevator 275 and provide follow-up for the space reference gyroscope 256, the output of which controls the antenna 217 in elevation by means of elevation servomotor 250.

Thus the missile and the antenna are provided with means for control in both azimuth and elevation.

The invention described herein may be manufactured and used by or for the Government of the United States of America for governmental purposes without the payment of any royalties thereon or therefor.

What is claimed is:

1. A movable object having control surfaces including azimuth and elevation control surfaces, radar means including an antenna carried by said movable object for providing sensing voltages indicative of the direction of the received waves, means responsive to the output of said radar means to control said antenna in azimuth and elevation, a first reverse-connected gyroscope having an adjustable stabilization axis and pick-off means to control said elevation control surfaces, said stabilization axis being controlled by the action in elevation of said antenna and further controlled by the action of said elevation control surfaces, a control means, a second reverse-connected gyroscope having an adjustable stabilization axis and pick-off means to control said control means, said stabilization axis being controlled by the action in azimuth of said an-

tenna and further controlled by said control means and a stable vertical gyroscope with an adjustable stabilization axis and pick-off means to control said azimuth control surfaces, said stabilization axis being controlled by said control means and further controlled by the action of said azimuth control surfaces, whereby the overall control including the correction provided by the reverse-connected gyroscopes directs said movable object along an intercept course to a target detected by said radar means.

2. A movable object having control surfaces including azimuth and elevation control surfaces, radar means including an antenna carried by said object for providing sensing voltages indicative of the direction of the received waves, first means responsive to the output of said radar means to control said antenna in azimuth and elevation, second means to control said elevation control surfaces, a first reverse-connected gyroscope having an adjustable stabilization axis and pick-off means to control said elevation control surfaces through said second control means, said stabilization axis being controlled by the action in elevation of said antenna and further controlled by the action of said elevation control surfaces through said second control means, third control means, a second reverse-connected gyroscope having an adjustable stabilization axis and pick-off means to control said third control means, said stabilization axis being controlled by the action in azimuth of said antenna and further controlled by said third control means, fourth means to control said azimuth control surfaces, and a stable vertical gyroscope with an adjustable stabilization axis and pick-off means to control said azimuth control surfaces through said fourth control means, said stabilization axis being controlled by the action in azimuth of said antenna and further controlled by said fourth control means; whereby the overall control including the correction provided by the reverse-connected gyroscopes directs the movable object along an intercept course to a target detected by said radar means.

3. The apparatus described in claim 2 wherein the first, second, third and fourth control means are servomotors.

4. The apparatus described in claim 2 wherein the first, second and fourth control means are servomotors, and the third control means is a proportional roll trim motor.

5. A movable object having control surfaces including rudder, elevator and aileron control surfaces, radar means including an antenna carried by said movable object for providing sensing voltages indicative of the direction of the received waves, first means responsive to the output of said radar means to control said antenna in azimuth and elevation, second means to control said elevator surfaces, a first reverse-connected gyroscope having an adjustable stabilization axis and pick-off means to control said elevator surfaces through said second control means said stabilization axis being controlled by the action in elevation of said antenna and further controlled by the action of said elevator surfaces through said second control means, a third control means, a second reverse-connected gyroscope having an adjustable stabilization axis and pick-off means to control said third control means said stabilization axis being controlled by the action in azimuth of said antenna and further controlled by said third control means, fourth control means to

control said aileron and rudder surfaces, and a stable vertical gyroscope with an adjustable stabilization axis and pick-off means to control said aileron and rudder surfaces through said fourth control means said stabilization axis being controlled by said third control means and further controlled by the action of said aileron and rudder surfaces through said fourth control means, whereby the overall control including the correction provided by the reverse-connected gyroscopes directs the movable object along an intercept course to a target detected by said radar means.

6. The apparatus as described in claim 5 wherein the first, second, third and fourth control means are servomotors.

7. The apparatus described in claim 5 wherein the first, second and fourth control means are servomotors, and the third control means is a proportional roll trim motor.

8. A movable object having control surfaces including azimuth and elevation control surfaces, radar means including an antenna carried by said movable object for providing sensing voltages indicative of the direction of the received waves to control said elevation control surfaces, a first reverse-connected gyroscope having an adjustable stabilization axis and pick-off means to control said antenna in elevation said stabilization axis being controlled by the action of said elevation control surfaces and further controlled by the action in elevation of said antenna, a control means responsive to the output of said radar means, a second reverse-connected gyroscope having an adjustable stabilization axis and pick-off means to control said antenna in azimuth said stabilization axis being controlled by said control means and further controlled by the action in elevation of said antenna, and a stable vertical gyroscope having an adjustable stabilization axis and pick-off means to control said azimuth control surfaces said stabilization axis being controlled by said control means and further controlled by the action of said azimuth control surfaces, whereby the overall control including the correction provided by the reverse connected gyroscopes directs said movable object along an intercept course to a target detected by said radar means.

9. A movable object having control surfaces including azimuth and elevation control surfaces, radar means including an antenna carried by said movable object for providing sensing voltages indicative of the direction of the received waves, first means to control said antenna in elevation, second means responsive to the output of said radar means to control said elevation control surfaces, first reverse-connected gyroscope having an adjustable stabilization axis and pick-off means to control said first control means said stabilization axis being controlled by said second means and further controlled by the action in elevation of said antenna, third means to control said antenna in azimuth, fourth means responsive to the output of said radar means, a second reverse-connected gyroscope having an adjustable stabilization axis and pick-off means to control said third control means said stabilization axis being controlled by said fourth means and further controlled by the action in azimuth of said antenna, fifth means to control said azimuth control surfaces, and a stable vertical gyroscope having an adjustable stabilization axis and pick-off means to control said azimuth control surfaces through said fifth control means said stabilization axis being controlled by said fourth

control means and further controlled by the action of said azimuth control surfaces, whereby the overall control including the correction provided by the reverse-connected gyroscopes directs the movable object along an intercept course to a target detected by said radar means.

10. The apparatus described in claim 9 wherein the first, second, third, fourth and fifth control means are servomotors.

11. The apparatus described in claim 9 wherein the first, second, third and fifth control means are servomotors, and the fourth control means is a proportional roll trim motor.

12. A movable object having control surfaces including rudder, elevator and aileron control surfaces, radar means including an antenna carried by said movable object for providing sensing voltages indicative of the direction of the received waves, first means to control said antenna in elevation, second means responsive to the output of said radar means to control said elevator surfaces, first reverse-connected gyroscope having an adjustable stabilization axis and pick-off means to control said first control means said stabilization axis being controlled by said second means and further controlled by the action in elevation of said antenna, third means to control said antenna in azimuth, fourth means responsive to the output of said radar means, a second reverse-connected gyroscope having an adjustable stabilization axis and pick-off means to control said third control means said stabilization axis being controlled by said fourth means and further controlled by the action in azimuth of said antenna, fifth means to control said rudder and aileron surfaces, and a stable vertical gyroscope having an adjustable stabilization axis and pick-off means to control said rudder and aileron surfaces through said fifth control means said stabilization axis being controlled by said fourth control means and further controlled by the movement of said rudder and aileron surfaces, whereby the overall control including the correction provided by the reverse-connected gyroscopes directs the movable object along an intercept course to a target detected by said radar means.

13. The apparatus described in claim 12 wherein the first, second, third, fourth and fifth control means are servomotors.

14. The apparatus described in claim 12 wherein the first, second, third and fifth control means are servomotors, and the fourth control means is a proportional roll trim motor.

15. A movable object having control surfaces including azimuth and elevational control surfaces, radar means including an antenna carried by said movable object for providing elevation and azimuth voltages indicative of the position of the source of received waves, a stable vertical gyroscope for controlling said azimuth control surfaces, control means for controlling said stable vertical gyroscope, a first reverse-connected gyroscope cooperating with the elevation output voltages of said radar means for controlling said elevation control surfaces and for controlling said antenna in elevation, a second reverse-connected gyroscope cooperating with the azimuth output voltages of said radar means for controlling said control means and for controlling said antenna in azimuth, whereby the overall control including the correction provided by the reverse-connected gyroscopes directs said movable object along an intercept course to a target detected by said radar means.

16. A movable object having control surfaces

including azimuth and elevation control surfaces, radar means including an antenna carried by said movable object for providing elevation and azimuth voltages indicative of the position of the source of received waves, first means for operating said azimuth control surfaces, a stable vertical gyroscope for controlling said first means, second means for controlling said stable vertical gyroscope, third means for controlling said elevation control surfaces, fourth means for controlling said antenna in elevation, a first reverse-connected gyroscope cooperating with the elevation output voltages of said radar means for controlling said third and fourth means, fifth means for controlling said antenna in azimuth, a second reverse-connected gyroscope cooperating with the azimuth output voltage of said radar means for controlling said second and fifth means, whereby the overall control including the correction provided by the reverse-connected gyroscopes directs said movable object along an intercept course to a target detected by said radar means.

17. The apparatus as described in claim 16 wherein the first, second, third, fourth and fifth means are servomotors.

18. The apparatus described in claim 16 wherein the first, third, fourth and fifth means are servomotors, and the second means is a proportional roll trim motor.

19. A movable object having control surfaces including rudder, elevator and aileron control surfaces, radar means including an antenna carried by said movable object for providing elevation and azimuth voltages indicative of the position of the source of received waves, first means for operating said rudder and aileron con-

trol surfaces, a stable vertical gyroscope for controlling said first means, second means for controlling said stable vertical gyroscope, third means for controlling said elevator control surfaces, fourth means for controlling said antenna in elevation, a first reverse-connected gyroscope cooperating with the elevation output voltages of said radar means for controlling said third and fourth means, a fifth means for controlling said antenna in azimuth, a second reverse-connected gyroscope cooperating with the azimuth output voltages of said radar means for controlling said second and fifth means, whereby the overall control including the correction provided by the reverse-connected gyroscopes directs said movable object along an intercept course to a target detected by said radar means.

20. The apparatus as described in claim 19 wherein the first, second, third, fourth and fifth means are servomotors.

21. The apparatus as described in claim 19 wherein said first, third, fourth and fifth means are servomotors, and the second means is a proportional roll trim motor.

Certificate of Correction

Patent No. 2,512,693

June 27, 1950

EARL C. SPARKS, JR., ET AL.

It is hereby certified that error appears in the printed specification of the above numbered patent requiring correction as follows:

Column 7, line 38, for "intecpt" read *intercept*; line 52, for "missible" read *missile*;

and that the said Letters Patent should be read as corrected above, so that the same may conform to the record of the case in the Patent Office.

Signed and sealed this 17th day of October, A. D. 1950.
